UNITED STATES PATENT OFFICE.

FREEBORN F. RAYMOND, 2d, OF NEWTON, MASSACHUSETTS.

NAIL DISTRIBUTING AND DRIVING MACHINE.

SPECIFICATION forming part of Letters Patent No. 356,209, dated January 18, 1887.

Application filed October 8, 1886. Serial No. 215,657. (No model.)

To all whom it may concern:

Be it known that I, FREEBORN F. RAYMOND, 2d, of Newton, in the county of Middlesex and State of Massachusetts, a citizen of the United States, have invented a new and useful Improvement in Nail Distributing and Driving Machines, of which the following is a full, clear, and exact description, reference being had to the accompanying drawings, forming a part of this specification, in explaining its nature.

The invention is an improvement upon that described in the Towns and Raymond Patent No. 346,137, and in my application filed August 28, 1886, Serial No. 212,040; and it relates, essentially, to the arrangement and combination, in an organized machine, of an apparatus or mechanism for supplying fastenings through a stationary throat or passage, a movable distributer having a number of holes or passages for receiving and guiding the nails or fastenings to a carrier or directly to the nail-driving devices, which is provided, preferably, with an intermittent movement in relation to said throat to bring its receiving holes or passages successively in line therewith, and with a continued return movement to bring the discharge-outlets of its holes or passages into a relation to the nail-carrier or to the nail-driving devices for the delivery of nails or fastenings thereto.

It further relates to the arrangement and combination, in an organized machine, of the fastening, feeding, or supplying device having a stationary throat or passage, the movable distributer having the movements indicated, and nail-driving devices arranged to drive the nails or fastenings as a gang or group.

It further relates to various details of construction, as will hereinafter appear.

In the drawings, Figure 1 is a view in rear elevation of the upper part of the machine containing the features of my invention. Fig. 2 is a side elevation thereof. Fig. 3 is a vertical section upon the line xx of Fig. 1. Fig. 4 is a horizontal section upon the line yy of Fig. 1. Fig. 5 is a horizontal section upon the line zz of Fig. 1. Figs. 6, 7, and 8 show a slight modification of the construction hereinafter referred to. Fig. 9 is a detail view in rear elevation to illustrate various parts in a different position from that represented in Fig. 1. Fig. 10 is a perspective view with a part of the nail-distributer attached. Fig. 11

is a view principally in plan, enlarged to represent the nail-strip feed and detent-paws.

As there are many machines which make fastenings, and machines for sorting or arranging fastenings held in bulk, which are adapted or arranged to feed or deliver fastenings in successive and regular order through a stationary throat, I would here say that I do not confine myself to the especial form of mechanism herein shown for delivering or feeding through a stationary throat fastenings in successive and regular order. I have shown for this purpose a device adapted to sever nails from a comb-strip, and to deliver them through the stationary throat in succession. It comprises a feeding device for feeding the comb-strip with an intermittent feed, a detent for holding or locking the strip stationary after it has been fed and during the return movement of the feed, and a plunger or punch which is reciprocated to sever nails in succession from the end of the strip and move them downward through the throat to the nail-distributer.

a represents the feed-pawl of this device. It may be reciprocated by a cam, as described in my said application, or as hereinafter described.

a' is the detent, which is in every respect like that of my said application.

a^2 is the plunger or punch, and a^3 the throat, and they are like the plunger and throat of the fastening making or severing device of my said application, with the exception that the throat is stationary. The plunger is reciprocated by the cam b on the shaft B.

The distributer which I have represented is adapted to supply nails or fastenings to a movable nail carrier or receiver, which receives them in the form of a group and advances them in that form to group-nailing devices. The distributer should have passages or holes arranged in a straight line at their upper ends, and brought into any desired arrangement for the delivery of fastenings at their lower end; and as the machine which I have shown in the drawings is organized for heel-nailing, the distributer is shown as arranged to deliver a gang or group of fastenings adapted to attach a heel-blank. It is probably best formed by a block, C, having the straight line of holes c arranged therein at a uniform distance from each other, and a block, c' , having holes c^2 arranged in a line in which it is desired to drive the nails.

This block c' is below the block C, and the holes c are connected with the holes c^2 by means of passages c^3 , formed by the tubes c^4 . This block c' has a sliding hole-covering plate, 5 c^5 , which is closed and held closed by a spring, and is opened upon the movement of the nail-carrier D by contact of a pin thereon with the edge of the plate when the carrier has been moved so as to bring its nail-receiving holes in o line with the holes of the block c' .

The distributor is mounted in or upon the traveling support or carriage E, shaped in plan substantially as shown in Fig. 5, having the space e for the reception of the block c' of the distributor, and also a support or ledge, e' , about the opening e , upon which the flange c^2 of the block c' rests. The distributor is held in place in this recess by the swinging latch-bar e^3 . The support or carriage E also has the o extension e^4 , and it is supported upon the bed or table F, which has guides f and cap-plates f' , which project upon the upper surface of the carriage E.

The distributor-support E is given an intermittent feeding movement to bring the holes c in successive order in line with the stationary throat a^3 , and to provide it with this movement I have arranged upon the section or arm e^4 of the carriage E a rack, G, which is attached to o the arm e^4 by screws, or in any other desired way, and I have arranged above the rack, to engage therewith, a worm, g , which is mounted upon the shaft g' . This worm has a thread so shaped that upon engagement with the tooth 5 of the rack it advances the support or carriage E during a part of the rotation of the shaft g' , and holds it stationary during the remainder of said rotation. This worm is well represented in Figs. 1 and 5. It is operated by the bevel-gear g^2 at its end and the bevel-gear g^3 at the lower end of the vertical shaft g^4 , which shaft is connected with the shaft B by the bevel-gear $g^5 g^6$.

The worm-shaft g' is supported by a support 5 or arm, g^7 , adapted to permit the upward movement of the end of the worm-shaft g' and disengage the worm g from the rack. There is secured to the arm g^7 a block, g^8 , which has an inclined or cut-away surface, g^9 . There is o arranged upon the arm g^7 an adjustable tripping-block, H, which is in substance like that described in the Towns and Raymond patent referred to, and it governs the number of nails delivered to the distributor. It is adapted to be moved and secured in any desired position upon the arm e^4 or the rack-bar, and its upper surface is arranged to come in contact with the under surface of the block g^8 , to lift the worm from engagement with the teeth of the rack when it is desired to stop the delivery of nails to the distributor.

In order that the carriage E may be immediately returned to its original position upon the disengagement of the worm from the rack, which of course will withdraw the support H from the block g^8 , it is necessary to bring into operation a device for holding the worm

from contact with the rack during this return movement of the carriage, and this I have represented in the form of a notched arm, M, 70 extending upward from the swinging support or arm g^7 , and which has the two shoulders $m m'$, one above and back of the other. There is arranged above this notched arm M a lever, m^2 , which is pivoted at m^3 , and has the downward-bent end m^4 , (see Fig. 1,) which is adapted to rest upon the shoulder m' when the worm is in contact with a tooth of the rack, and upon the shoulder m' when the worm and its swinging arm g^7 have been lifted by the block H. 80 This gives the latch-lever m^2 two positions, and enables it to be used in operating the shipping-lever P, as hereinafter described. It is moved automatically to release the arm M by means of a cam on the shaft of the heel-nailing machine (not shown) and a connecting-rod, m^5 . The organization is such that the cam gives the latch-bar an upward movement to release the notched arm, and therefore the worm, which then drops into place to engage with 90 the teeth of the rack-bar.

I do not confine myself to the especial mechanism for moving the distributor forward with an intermittent movement, as I may employ any equivalent for the worm and rack. I 95 would further say that the distributor may be arranged in relation to the carrier so as to deliver its nails thereto upon the end of its forward movement, instead of at the end of its reverse movement.

The position of the latch-bar shipping-lever and worm and its support when the machine is in operation is shown in Fig. 1, and when the machine is stopped or the worm lifted to permit the movement of the distributor, as 105 shown in Fig. 9, of course the worm is held from engagement with the rack during the backward movement of the distributor and its carriage or support E to a position to deliver fastenings to the nail-carrier. Any suitable means may be employed for giving the carriage or support this motion, and I have represented the weight n , attached to the rack by a cord passing over the pulley n' , connecting the worm e^4 with the weight, for accomplishing this purpose. The upward movement of the worm-shaft to disengage the worm also causes the end of the shipping-lever P to fall into a position to be moved horizontally by the lever p' , operated by the cam p^2 . This 120 pushes the driving member p^3 of the clutch from the driven member, and also causes a friction-brake (not shown) to bear against the driven member of the clutch, and the machine immediately comes to rest.

To start the machine it is simply necessary to raise the end of the shipping-lever P from engagement with the latch-lever p' , as this permits the spring p^5 to draw the driving member of the clutch into contact with the driven member of the clutch, and this is accomplished by means of the push-rod p^4 , which is connected with the latch-lever.

The distributor is applicable to any fasten-

ing forming or separating machine adapted to deliver fastenings through two or more throats simultaneously or successively without essential difference in the organization of the distributor. The difference in its operation when so used is that it is moved a greater distance by its feeding mechanism to move the holes receiving nails out of register with the throat and new or other holes into register therewith.

10 For the purposes of this invention it is not essential that the nail-distributer include the nail-holder, as the tools may be arranged to deliver nails or fastenings directly to the nail-driving devices or to the nail-carrier. Still, 15 for ordinary purposes it is preferable that the tubes be brought together at their lower ends and held by some connection which shall be an equivalent of the nail-holder and block, and it is also desirable that the two shall be 20 connected at their upper ends by a plate or block. The cam p^2 may be used through the lever p for operating the support or slide for the feed-pawl a , the support being connected with the end of the lever by means of a link, 25 P' . This construction is represented in the drawings.

The distributer, instead of being secured to the carriage or support E , as above described, may be fastened or bolted to the end thereof 30 by means of the two rods $P^2 P^3$, which are fast to the ends of the carriage and are adapted to enter holes in the block c' of the distributer, and nuts. This construction is shown in Figs. 2, 3, and 5 of the drawings.

35 In use, upon the release of the driving member of the clutch it is drawn into contact with the driven member. Simultaneously with this movement the worm-shaft for driving the distributer is released and the worm engages the 40 rack on the carriage E . The nail-strip feeding and severing mechanism immediately begins to operate, and nails are severed from the end of the comb-strip in successive order and delivered through the throat of the machine 45 through the holes of the distributer as it is intermittently moved forward to bring them in register therewith in successive order. This portion of the mechanism continues its operation until a sufficient number of fastenings 50 have been delivered to the distributer, when the block determining the number of fastenings to be delivered comes in contact with the projection connected with the worm-shaft, lifts the worm-shaft, disengages the worm from the

55 rack, brings the worm-shaft-holding latch into position to hold the shaft and worm elevated, and causes a connection between the cam and the driving member of the clutch, whereby it is unshipped and a brake applied, and brings 60 into operation the weight for returning the distributer to its original position. The nail-carrier is then moved beneath the distributer, if not already in that position, and the sliding hole-covering plate moved and a gang or group 65 of fastenings delivered to the carrier. The carrier then moves forward sufficiently to per-

mit the sliding plate to close the holes of the distributer, and then nail feeding and distributing devices are automatically set in operation to make another load of nails. Meanwhile 70 the carrier is moved to deliver its load of nails to the nail-driving devices.

The movement of the distributer is intermittent while receiving fastenings from the throat a^3 , and is continuous during the reverse 75 movement. The weight serves to keep the teeth of the rack in contact with the edge of the arm, so that there is no backlash and the holes of the distributer are always brought into active register with the throat. 80

The worm is shaped to perform two functions: first, it moves the distributer the distance between the centers of two holes in the block C , and after thus moving it into the holes the block is locked in that position while the 85 nail or fastening is being delivered to a hole therein from the throat. The arm of course does not stop its rotation, and the effect is produced entirely by the shape of the thread of the worm. 90

I may use, in lieu of the worm and rack feed, a ratchet-bar or any other equivalent device for providing the distributer with this intermittent movement. The movement of the distributer may be the reverse of that above indicated—that is, it may be continuous on its outward movement and intermittent upon its return—in which case it would receive the fastenings from the throat upon the return movement and would deliver them to the nail-carrier and nail-driving devices and then return to its original position, to again be moved forward. 95

The nail-carrier and nail-driving devices are similar to those described in various of my patents. 100

I am aware that in Patent No. 346,137 and in Patent No. 347,960 there is described a nail making and distributing machine having stationary nail-making devices, a stationary distributer, and an intermediate movable nail-receiving block, which receives the nails from the nail-making machine or devices and delivers them to the stationary distributer, while in the invention herein described I dispense 115 entirely with the intermediate movable block above referred to, and use a movable distributer instead of a stationary distributer; and I would say that I do not claim herein anything shown and described in said patents. 120

Having thus fully described my invention, I claim and desire to secure by Letters Patent of the United States—

1. The combination, in a nail distributing and driving machine, of a plate or nozzle having a throat through which fastenings are fed in successive order, a distributer having a series of holes and distributing passages connected therewith, and a movable sliding plate or carriage, substantially as described, upon which the distributer is mounted, movable upon a straight line in relation to said throat 125 130

and acting to bring the holes thereof substantially in register with the throat, substantially as described.

2. The combination, in a nail distributing and driving machine, of a plate or nozzle having a throat, a distributor having a series of holes and distributing passages connected therewith, a slide plate or carriage upon which the distributor is mounted, and feeding mechanism, substantially as described, for advancing the carriage or plate with an intermittent movement while it is receiving the fastenings, and a tripping block or device for tripping the feeding mechanism upon the delivery of a predetermined number of nails to the distributor, substantially as described.

3. The combination of a plate or nozzle having a throat, a distributor having a series of holes and guiding tubes or passages connected therewith, a slide plate or carriage for supporting the distributor, mechanism, substantially as specified, for feeding the carriage with an intermittent movement while the distributor is receiving fastenings, a tripping block or device for tripping the feed upon the delivery of a predetermined number of nails to the distributor, and mechanism, substantially as specified, for returning the distributor to its original position upon the release of the feed, substantially as described.

4. The combination of a plate or nozzle having a throat through which fastenings are adapted to be delivered in successive order, a distributor having a series of holes and guiding passages or tubes extending therefrom, a sliding plate or carriage supporting said distributor, a nail-carrier for receiving nails, as a gage or group, from the distributor and transferring them to the nail-driving devices, and suitable nail-driving devices, substantially as described.

5. The combination of a plate or nozzle having a throat, a^3 , a reciprocating plunger or punch, a^2 , mechanism for feeding a nail-strip thereto, the shaft B, the distributor having a series of holes, and guiding tubes or passages connected therewith mounted upon a slide plate or carriage, and means, substantially as specified, for providing said carriage with an intermittent movement to bring the holes of the distributor in successive register with the throat, substantially as described.

6. The combination of the slide plate or carriage E, and a removable nail-distributer carried or supported thereby, comprising the block C, having the holes c , block c' , having the holes c^2 , and connecting device c^3 , substantially as described.

7. The combination of the slide plate or carriage E, having a recess, e , with a nail-distributer having a block, e' , provided with the extension e^2 , to rest upon the shoulder e' of the plate E, substantially as described.

8. The combination of the bed F, having guides f and cap-plates f' , with the slide or carriage E, and a multiple nail-distributer mounted thereon, substantially as described.

9. The combination of the bed F, the plate E, movable thereon and supporting a multiple fastening-distributer, the rack G, and the worm g , having its thread formed as described, substantially as set forth.

10. The combination of the bed F, the slide plate or carriage E, supporting a multiple nail-distributer, the rack G, the worm g , its shaft g' , the swinging block or arm g^2 and its block g^3 , and the adjustable tripping-block H upon the plate E, substantially as described.

11. The combination of the bed F, the slide plate or carriage E, supporting a multiple fastening-distributer, the rack G, the worm g , its shaft g' , supported at one end by the swinging arm g^2 in a manner to permit the worm to be disengaged from the rack, with an automatic latch, M m^2 , for holding the worm-shaft and the worm disengaged from the rack, substantially as described.

12. The combination of the bed F, the guides f , and cap-plates f' , and the slide plate or carriage E, supporting a multiple nail-distributer, with the weight N and cord n , substantially as described.

13. The combination of the bed F, guides f , and cap-plates f' , the slide plate or carriage E, supporting a nail-distributer, the rack G, the worm g , the swinging movable worm-shaft g' , the tripping-block H, the worm-shaft-holding latch m^2 , the driving and driven members of the clutch, and mechanism connecting the driving member with the worm-shaft g' , whereby upon its movement the driving member is disengaged from the driven member and the machine comes to rest, substantially as described.

14. The combination of the plate F, guides f , the cap-plates f' , the slide plate or carriage E, supporting a multiple nail-distributer, the rack H, the worm g , its shaft g' , the tripping-block H, the worm-shaft-holding latch m^2 , the driven and driving members of the clutch, and a device for unlatching the driving member of the clutch and for disengaging the worm-shaft latch from the shaft, substantially as and for the purposes described.

15. The combination of the shaft B, operating the nail-strip feeding and severing mechanism, the bed F, its guide f , the cap-plate f' , the slide plate or carriage E, carrying a multiple nail-distributer, the rack G, the worm g , its shaft g' , the shaft g^2 , connecting it with the shaft B, the driven and driving members of the clutch, and a cam carried by the shaft B for operating the shipping-lever to disengage the driving from the driven member of the clutch, substantially as described.

16. The combination of the slide plate or carriage E, supporting a multiple nail-distributer, the rack G, the worm g , the shaft g' , its support g^2 , the worm-shaft-holding latch m^2 , and the push-rod m^3 , substantially as described.
